Attorney

UNITED STATES PATENT OFFICE.

WILLIAM H. HOWARD, OF STOUGHTON, MASSACHUSETTS.

CLOTH-CARRIER.

SPECIFICATION forming part of Letters Patent No. 783,787, dated February 28, 1905.

Application filed June 17, 1904. Serial No. 213,019.

To all whom it may concern:

Be it known that I, WILLIAM H. HOWARD, a citizen of the United States, residing at Stoughton, in the county of Norfolk and State of Massachusetts, have invented certain new and useful Improvements in Cloth-Carriers; and I do hereby declare the following to be a full, clear, and exact description of the invention, such as will enable others skilled in the art to 10 which it appertains to make and use the same.

This invention relates to machines or devices for supporting cloth or other similar material in the forms of folds while in a drying-machine or stove; and it consists in the novel 15 construction and combination of the parts hereinafter fully described and claimed.

In the drawings, Figure 1 is a side view of the machine. Fig. 2 is a plan view of the machine. Fig. 3 is a cross-section through one 20 of the guides, showing one of the spacing-carriages.

The machine is provided with two parallel guides A, and each guide consists of two upper bars *a* and two lower bars *b*, arranged in 25 pairs with spaces between them. These guides are supported in a horizontal position by means of uprights B or any other suitable supports, and the whole machine is inclosed in a stove or any approved form of drying-machine, which is not more fully shown in the 30 drawings, as it does not form a part of the present invention. The front end portions A' of the guides are connected to their main portions by hinges *c* and are provided with fastening devices *c'* for holding them in position. When the machine is loaded with cloth, the front end portions of the guides are turned 35 downward on their hinges, so that the stove-door may be closed. The dotted lines *t* in Fig. 1 indicate a portion of the stove-door.

C is the driving-shaft, journaled in bearings at the front end portions of the guides and driven by any suitable means, such as a driving-pulley C'. A similar driving-shaft C and driving-pulley C' is provided at the other side 45 of the machine, so as to leave room for the entrance of the folds of cloth at the middle part of the machine between the ends of the two said shafts C.

50 This cloth-carrier is preferably arranged to

work in connection with the folding-machine for which a patent was issued to me on June 23, 1903, No. 731,905.

D represents the bars which support the cloth D' in the form of loops or folds, and *d* 55 represents the flexible connections which couple the bars D together in a series. The folding-machine delivers the bars and the folds of cloth onto the front end of the machine, and the machine is provided with mechanism 60 for sliding the bars and cloth rearwardly on the guides and arranging the said bars at pre-arranged equal distances, so that the folds of cloth can be dried to the best advantage. As each guide is provided with similar spacing 65 and driving mechanism, the description will be confined to the devices at one side of the machine.

E is a pulley secured on the shaft C between the guide-bars, and E' is a similar pulley secured on a shaft *e*, which is journaled in a suitable bearing-bracket *e'* at the rear part of the machine. F is a belt or other similar flexible driving connection which passes over the said pulleys. A toothed driving-wheel, *f* 75 is also secured on the shaft *e*.

G is a winding-shaft which extends cross-wise of the guides at the rear part of the machine and which has a winding-barrel *g* secured on it. This winding-shaft rests on the 80 guides and is slidable upon them to a limited extent. A toothed pinion *f'* is secured upon each end of the shaft G, and these pinions engage with the said wheels *f*, so that the winding-barrel may be revolved.

H is a cord, chain, or other flexible connection which is wound on the barrel and secured to the first cross-bar D, which slides on the guides.

I is a lever pivoted on a pin *i*, which projects from one of the guide-bars. A rod *i'* is pivoted to the upper end of this lever and engages with the shaft G.

J is a trip-lever pivoted to a pin *j*, which projects from one of the guide-bars, and *j'* is 95 a connecting-rod pivoted to the lower end of the trip-lever and to the lower end of the lever I.

One of the upper guide-bars *a* is provided with a toothed rack *k*.

100

K is a carriage which slides upon the lower guide-bars b.

M represents guide-pulleys which are journaled in the end portions of the carriage.

5 N is a belt-pulley which is secured on a shaft n, which is journaled at the middle part of the carriage.

The driving-belt F, hereinbefore described, passes under the guide-pulleys M and over the pulley N, so that the shaft n is revolved continuously. A toothed wheel or sprocket-wheel m is also secured on the shaft n and operates as a spacing-wheel for the bars which support the cloth.

15 A toothed pinion p is secured upon the shaft n and is arranged so as to gear into the rack k.

P represents rollers on the shaft n, which run on the lower guide-bars b, so that the carriage may run easily.

20 R is a trip-lever pivoted to one of the guide-bars in the path of the bars D and which engages with the shaft n or any convenient part of the carriage.

The operation of the machine is as follows:

25 When the machine is started, the pinions p are out of gear with the racks, as shown in the drawings, and the pinions f' are in gear with their driving-wheels. The winding-shaft is

30 revolved so as to wind the chain on the barrel and draw the bars D and the folds of cloth rearwardly along the guides. The bars D are dragged over the spacing-wheels m, and when the first bar D is drawn against the trip-levers J it slides the winding-shaft rearwardly, so

35 that the pinions f' are placed out of gear with their driving-wheels and the barrel is no longer revolved. Before the first bar D strikes the trip-levers J, however, it strikes the trip-levers R and turns them on their pivot-

40 pins. These trip-levers R push the carriages forward so that the pinions p engage with the racks k at about the same time that the winding-barrel is thrown out of action. The carriages commence to slide forward on their

45 guide-bars, and the bars D are drawn over the spacing-wheels m and deposited on the guides at prearranged equal distances apart, according to the proportions of the various parts of the driving mechanism. When the 50 carriages arrive at the front ends of the guides, the machine is loaded with cloth in the form of folds. The machine is then stopped, and the cloth is dried while supported in the form of folds or loops by the said bars D.

55 What I claim is—

1. In a cloth-carrier, the combination, with parallel guides provided with hinged front end portions, of means for holding the said front end portions in line with the main portions, and 60 spacing mechanism for arranging the cloth upon the said guides.

2. In a cloth-carrier, the combination, with guides for the bars which support the cloth, of a toothed driving-wheel journaled at the rear

end of the said guides and provided with 65 means for revolving it, a slidable winding-shaft supported by the guides, a flexible connection between the said shaft and the said bars, a toothed pinion secured on the said shaft, and trip-lever mechanism for sliding the said 70 shaft and moving the said pinion into and out of gear with the said driving-wheel.

3. In a cloth-carrier, the combination, with guides for the bars which support the cloth, of a toothed driving-wheel journaled at the 75 rear end of the said guides and provided with means for revolving it, a slidable winding-shaft supported by the guides, a flexible connection between the said shaft and the said bars, a toothed pinion secured on the said 80 shaft, a lever pivoted to one of the said guides, a rod pivoted to the upper end of the said lever and to the said shaft, a trip-lever also pivoted to one of the said guides and arranged in the path of the said bars, and a connecting-rod between the lower part of the said trip-lever and the lower part of the aforesaid lever. 85

4. In a cloth-carrier, the combination, with guides for the bars which support the cloth, and a toothed rack carried by one of the said 90 guides, of a spacing-carriage slidable in the said guides, a spacing-wheel carried by the said carriage, a toothed pinion revolving the said spacing-wheel, driving mechanism for revolving the said wheel and pinion, and a trip-lever 95 for placing the said pinion into engagement with the said rack,

5. In a cloth-carrier, the combination, with guides for the bars which support the cloth, and a toothed rack carried by one of the said 100 guides, of a spacing-carriage slidable in the said guides, a belt-pulley and two guide-pulleys journaled in the said carriage, driving-pulleys and a driving-belt which passes over all the said pulleys, a spacing-wheel which revolves with the said belt-wheel, a toothed pinion which revolves with the said spacing-wheel, and a trip-lever for placing the said pinion into engagement with the said rack. 105

6. In a cloth-carrier, the combination, with guides for the bars which support the cloth, of spacing-carriages slidable on the said guides and provided with spacing-wheels for engaging with the said bars, a winding-shaft journaled at the rear end of the said guides, driving devices which revolve the said winding-shaft and spacing-wheels simultaneously, mechanism for sliding the spacing-carriages and trip mechanism operated by one of the said bars, so that the winding mechanism is stopped 115 when the carriage-sliding mechanism is started.

In testimony whereof I affix my signature in presence of two witnesses.

WILLIAM H. HOWARD.
